UNITED STATES PATENT AND TRADEMARK OFFICE
CERTIFICATE OF CORRECTION

PATENT NO. : Des. 410,527

DATED : June 1, 1999

INVENTOR(S) : Jack Chang and Mike Hsu

It is certified that error appears in the above-identified patent and that said Letters Patent is hereby corrected as shown below:

On the title page item [56],

In the fourth publication citation under the "OTHER PUBLICATIONS" heading of the **References Cited** field, "23-219C" should read -- 24-219C --.

In the Claim, "facucet" should read -- faucet --.

Signed and Sealed this
Fourth Day of January, 2000

Attest:

Attesting Officer

Acting Commissioner of Patents and Trademarks
